COMBINED LETTER OPENER AND STAMP DRAWER

Edward J. Coyne, Minneapolis, Minn.

Application April 10, 1956, Serial No. 40,992

Term of patent 7 years

(Cl. D74—1)

Fig. 1 is a top plan view of a combined letter opener and stamp drawer showing my new design;

Fig. 2 is a side elevational view thereof;

Fig. 3 is an enlarged end elevational view as seen from the right of Fig. 2; and

Fig. 4 is a top perspective view of the stamp drawer as it appears removed from letter opener.

I claim:

The ornamental design for a combined letter opener and stamp drawer, as shown.
